ALLISON ANDREW CLOKEY, OF RUTHERFORD, NEW JERSEY, ASSIGNOR TO INTERNATIONAL STANDARD ELECTRIC CORPORATION, OF NEW YORK, N. Y.

TELEGRAPH SYSTEM

Application filed December 26, 1928, Serial No. 328,518, and in Great Britain October 17, 1928.

This invention relates to synchronous telegraph systems and particularly to such systems for use on cables of high capacity.

An object of the invention is to maintain synchronization between transmitting and receiving terminal equipment, and to eliminate false corrections of the receiving apparatus due to phase shift of the signals during transmission.

10 Synchronous telegraph systems heretofore employed have utilized synchronizing impulses derived from the received signal impulses themselves for synchronizing the receiving apparatus. This method has the advantages that the entire line time may be used for signal transmission and that synchronizing impulses occur at very frequent intervals.

However, there is an objection to synchronizing from signal impulses. It is that, even though the receiving apparatus be running in perfect phase adjustment with the transmitting apparatus, received signal impulses may, due to line distortion, arrive at the receiving 25 station out of phase with the receiving apparatus and cause false corrections which alternately advance and retard the phase of the receiving apparatus.

The phase shift in the received signals is caused primarily by the non-uniform nature 30 of the signal impulses. For instance, a preponderance of positive impulses during a given time interval may shift the phase of the received impulses in one direction and a preponderance of negative impulses may shift 35 the phase in the opposite direction.

To eliminate false corrections it is proposed, in accordance with this invention, to eliminate the use of signal impulses for correction purposes and to transmit at intervals, in place of signals, a series of clearing out impulses comprising a ground impulse, or a series of equal impulses of alternately opposite polarity, or both, and thereafter a special 45 synchronizing impulse. The grounding impulse and/or the series of pulses of alternately opposite polarity leave the cable in a neutral condition regardless of the character of the preceding signal impulses, so that successive synchronizing impulses, as received, al-

ways bear the same phase relation to the transmitting apparatus. The time required to neutralize the cable preparatory to the transmission of the synchronizing impulses is not available for signal transmission but the line time lost in this way may be reduced to a small proportion of the total line time by using very constant speed synchronous motors at the terminals, so that synchronizing impulses will be required only at relatively long intervals.

The invention will now be explained in detail with reference to the drawing, Fig. 1, of which comprises curves showing signals before and after transmission, Fig. 2 of which is a diagram representing schematically the apparatus at a transmitting station and Fig. 3, a diagram representing the apparatus at a receiving station. Fig. 4 shows the curve representing the phase of the received current relative to the segments of the receiving distributor.

Theory of the invention

An understanding of the manner in which this invention eliminates false corrections of synchronous receiving apparatus for cable signals may be readily conveyed with the aid of curves of signals as they are transmitted and received. In Fig. 1, the upper curve 75 represents a series of signal impulses as they are transmitted and curve 76 represents the same signals as they may appear after having been transmitted over a submarine cable, shaped, and amplified for the operation of signal recording and synchronizing equipment.

It will be noted that whereas the transmitted impulses are square topped, the received current rises gradually and requires appreciable time, following each reversal, to rise to a value sufficient to operate a receiving relay or a phase correcting relay. In connection with curve 76, the lines 77 and 79, above and below the zero axis 78, indicate the current values necessary to operate a phase correcting relay. Thus a positive impulse applied to the cable at time A does not increase the potential of the receiving end of the cable sufficient to operate a correcting re-

lay until time A' , .18 seconds later. Such time lag between transmission and reception is unavoidable and would have no bad effect were it uniform, but unfortunately it varies between wide limits depending on the sequence of signals transmitted. In the case illustrated it may vary from .12 seconds, at time J , to .18 seconds, at time A , depending on the sequence of preceding impulses.

In a system in which any or all of the received signal impulses are used for correction purposes, this non-uniform spacing of received impulses may cause needless false corrections because at time A' , a signal is received later, with respect to the distant transmitting distributor, than is the signal at time K' , although there has been no actual phase shift between the transmitting and receiving equipment.

But although, as indicated, there is a variation in the transmission time when heterogeneous impulses are sent, it will be seen that on sending pure reversals (from time F on) the transmission interval becomes constant after a few reversals. In accordance with this invention, synchronous corrections are made only following a train of reversals, or a grounding period, or some other treatment. The only requirement is that the treatment of the cable preceding correction be such as to restore it each time to a definite predetermined condition.

In the case illustrated the treatment is a series of reversals because that has been found satisfactory with some cables, but other methods may be more satisfactory under other conditions. Furthermore, with the method illustrated, the number of reversals necessary will vary with the length and type of cable and with the shaping networks used at the terminals. The treatment necessary to secure a uniform transmission interval may be determined for any application by methods well known in the art, such as by measurement of oscillographic records of received signals.

Description of apparatus

Referring to Fig. 2, a submarine cable 1, arranged for duplex operation, is connected by a conductor 2 to the common ring 3 of a transmitting distributor. For the purpose of explanation the distributor rings have been shown developed, but it is to be understood that in practice they would be in the form of a disc or cylindrical surface and that the brushes 4 and 5 would be revolved by a constant speed motor 7, which has been shown as a phonic wheel excited from a source of constant frequency current O .

Each of the segments successively associated by brush 4 with the common transmitting ring 3 is normally connected, either directly or through contacts associated with the relays 9 and 10, with one of the transmitting tongues of a tape transmitter. The system, as shown,

is arranged for four channel operation and comprises four tape transmitters, A B C and D. When no signals are being transmitted, all the tongues of the transmitting tongues lie against their left contacts, which in the case of channels A and C are connected to a current source of negative polarity, and in the case of channels B and D are connected to sources of current of positive polarity. When signals are being transmitted, the transmitting tongues are moved in response to the perforations in the transmitting tapes to transmit positive or negative impulses in accordance therewith.

To the right of the synchronous motor 7 is shown an automatic switch which is operated from the shaft of motor 7 and which closes, at definitely measured, long intervals, a circuit comprising relays 9 and 10 to cause the transmission of signal impulses to be interrupted for one complete revolution of the brushes 4 and 5 while the cable is stabilized, and synchronizing impulses are transmitted. Cam 21 closes contact 28 at relatively long intervals, while cam 22 geared directly to motor shaft closes contact 27 with greater precision relatively to position of brushes. A detailed description of the operation of relays 9 and 10 and the circuits controlled thereby will be given later.

In Fig. 3, the receiving common ring 12 of a receiving distributor and the associated printer apparatus in channels A B C and D is connected to the cable 1, across the arms of the duplex bridge comprising condenser 13 and 14. The receiving brushes 15 and 16, like those at the transmitting station, are revolved over their associated common and segmented rings by a constant speed motor 17 controlled by a tuning fork 18. The frequency of fork 18, and hence the speed of motor 17, may be regulated by shifting weight 19 along the tines of the fork. A mechanism 20 is shown for automatically regulating fork 18 under control of received synchronizing impulses. To the right of motor 17 is an automatic timing switch similar to that shown at the transmitting station in Fig. 1, and designed to close its contacts simultaneously with the mechanism at the transmitting station.

Operation of transmitting apparatus

Normally the brushes 4 and 5 at the transmitting station in Fig. 2 successively connect the tongues of the transmitters in the different channels A B C and D to the cable 1, and transmit impulses in accordance with the perforations in the transmitting tapes. This condition prevails for a predetermined period, which may vary from a few seconds to several minutes depending on the constancy of speed of the driving motors, at the end of which time, the cams 21 and 22 close their associated contacts, 28 and 27 simul-

taneously. The ratios of the speeds of cams 21 and 22 to each other and to the distributor shaft are so regulated that they close the contacts during an interval when the brushes 4 and 5 are travelling between segments 24 and 25, and remain closed during approximately one revolution and a half of brushes 4 and 5, i. e. until brushes 4 and 5 are travelling between segments 25 and 23 over channels C and D.

Following a closure of contacts 27 and 28, brush 5 applies ground from common ring 6 to segment 26, which closes a circuit through the winding of relay 9, conductor 29, resistance 30 and contacts 28, and 27 to battery 31. Current from battery 31 thereupon operates relay 9, which locks up over its front contact and remains operated until brush 5 has completed a revolution, and contacts with release segment 25. In the meantime, brush 5 contacts with segment 24 and operates relay 10 by closing a path from ground over common ring 6, through brush 5, segment 24, the winding of relay 10, conductor 32, resistance 33 and contacts 28 and 27 to the grounded battery 31. Relay 10 thereupon operates and locks up over its two independent tongues and front contacts against the opening of contacts 27 and 28. It is released by brush 5 applying ground to segment 23.

While brush 5 is travelling from segment 23 to segment 25, brush 4 crosses the transmitting segments associated with channels A and B. No signals are being transmitted from these channels at this time because the tape transmitters have been locked by their locking magnets 34 and 35, which were energized over the two lower tongues and contacts of relay 9 when the latter operated.

Since, when they are locked, the transmitting tongues of channel A lie against their negative contacts and the tongues of transmitter B lie against their positive contacts, channel A would transmit a series of 5 negative impulses and channel B a series of positive impulses. By the operation of relay 9, however, the first and second segments of channel A were disconnected from their associated transmitting tongues and connected to ground over the contacts 38 and 39, while the fourth segments was connected to positive battery over contact 40. At the same time, the second, third and fourth segments of channel B were disconnected from their associated transmitting tongues, the second and third segments being connected to ground at contacts 41, and the fourth segment being connected to negative battery at contacts 11. Before brush 4 reaches the segments of the 3rd and 4th channels the 2nd and 3rd and 4th segments of channels C and the 2nd and 3rd segments of channels D have also been switched, by relay 10, from their associated transmitting tongues, to connection with positive or negative battery as required to

cause the transmission of successive impulses of opposite polarity.

The net effect of the above changes is that during one revolution of the distributor brushes 4 and 5, no signals are transmitted but in lieu thereof, there is transmitted a series of grounding impulses and impulses of alternately opposite polarity.

During this revolution, brush 5 contacts with segment 25 for the first time since relay 9 was energized over segment 26. This applies ground over common ring 6, brush 5 and segment 25, to conductor 29, shunts the flow of current from battery 31 through the winding of relay 9, and causes the relay to release. This releases the tape transmitter magnets 34 and 35 in channels A and B and reconnects the transmitter tongues with their associated segments, so that when brush 4 begins its next revolution, signals will be transmitted from channels A and B. Relay 9 may re-energize on brush 5 again applying ground to segment 26 but the offering of contacts 27 and 28 before brushes 4 and 5 reach channels A and B will restore the signalling conditions. Brush 5 applies ground from common ring 6 over segment 23 to conductor 32, shunting the winding of relay 10 and causing the latter to release and as the contacts 27 and 28 are by this time open relay 10 does not energize again when brush 5 passes over contact 24. The release of relay 10 releases the transmitter locking magnets 36 and 37 in channels C and D and connects the transmitting tongues of those channels to their associated transmitting segments so that signal transmission will be also resumed from channels C and D.

Operation of receiving apparatus

Referring to Fig. 3, at the receiving station, cams 70 and 71 close their associated contacts 72 and 73 simultaneously with the contacts 27 and 28 at the transmitting station. Hence, when brush 16 contacts with segment 45, it closes a circuit from ground over common ring 46, segment 45, winding of relay 53, conductor 54, resistance 57, and contacts 72 and 73 to battery 58, whereupon relay 53 operates and locks up over its upper armature and grounded contact. It completes, at the same time, over its lower contacts, circuits including the windings of locking magnets 48 and 49 in channels A and B, which are thereupon energized.

The brushes continue their travel, and after a half revolution, close a circuit from ground over common ring 46, segment 43, the winding of relay 52, conductor 55, resistance 56 and contacts 72 and 73 to battery 58, which operates relay 52, the latter locking up over its upper armature and grounded contact, and also a lower tongue and contact against opening of contacts 72 and 73. By the operation of relay 52 the two inside

lower tongues 52 are connected to ground over their front contacts, which closes circuits from battery through the windings of printer locking relays 50 and 51 in channels 5 C and D. These relays thereupon operate and hence, during the revolution of the transmitting distributor when no signals are being transmitted, the locking magnets 48, 49, 50 and 51 at the receiving station are energized to prevent the receiving apparatus 10 from responding to the series of pulses of alternately opposite polarity which are transmitted for line clearing purposes.

Synchronizing the receiving apparatus

15 While the brushes at the transmitting end receiving stations are travelling over the segments associated with channels A B and C, any distorting influence on the cable due to 20 the history of previous signal impulses is being wiped out, and it is undesirable during this period that any correction be attempted at the receiving station. By the time the brushes have reached channel D, 25 however, the cable has been stabilized and received current reversals may be utilized for correction purposes without danger of making false corrections. Special synchronizing segments 59 and 60 are therefore inserted between the second and third, and between 30 the fourth and fifth receiving segments of channel D. There is no practical difficulty in inserting these extra segments at these points because it is customary to make the 35 receiving segments only a half or a third as long as the transmitting segments. Segments 59 and 60 being spaced equidistant between receiving segments, are in positions to receive reversals, that is assuming there is 40 no deviation from synchronism between the transmitting and receiving apparatus, brush 15 will connect segments 59 and 60 to the common ring 47 just as received current impulses are passing through zero, while changing 45 from positive to negative. This condition is shown to better advantage in Fig. 4. It will be seen by referring to Fig. 4, that if the receiving distributor is slightly out of phase with the transmitting distributor, the 50 wave 76 will be shifted forward or backward relative to segments 59 and 60, and either positive or negative impulses will be applied to segments 59 and 60. Since these 55 segments are connected, through contacts 61 on relay 52, to the winding of polar relay 62, the latter relay will move its tongue to the left or to the right in response thereto. If the receiving distributor is running in advance 60 of the received signals negative impulses will be applied over the segments 59 and 60 to polar relay 62, which will cause the tongue of that relay to move momentarily to the right and close a circuit from battery 63 through the relay tongue and right contact to 65 correcting magnet 64, which steps the ratchet

wheel 66 to the right and moves the weight 19 on the tuning fork 18 toward the end of the tines and reduces the speed of the fork. On the other hand, if the receiving apparatus is running slower than the sending apparatus, positive impulses will be applied to segments 70 59 and 60 and hence to relay 62, moving the tongue of the latter relay to the left. This applies current from battery 63 over the tongue and left contact of relay 62 to corrector magnet 65, which steps the ratchet wheel 67 to the left and moves weight 19 toward the base of the fork thus increasing its frequency and speeding up the receiving apparatus. 75

80 Although a simple tuning fork 18 has been shown as a source of oscillations for the constant speed motor 17, it is to be understood that the invention is not limited to the use of such apparatus. In fact, since for the 85 highest efficiency it is desirable with this system to correct only at long intervals, extremely constant speed drives should be utilized. Vacuum tube regenerative tuning forks have been developed to a high degree 90 of perfection and are desirable for use in this system. Furthermore, although means has been shown for correcting the speed of the receiving distributor in either direction, it is within the scope of this invention to cause 95 the receiving distributor to run either slightly faster or slightly slower than the transmitting distributor and to correct the receiving distributor periodically on one direction only. Systems employing both primary and secondary correction may also be used. Such 100 a system is disclosed in United States Patent to Pernot No. 1,647,468, patented November 1, 1927, in which the distributor arms carrying the brushes are stepped backward 105 or forward (clock hand correction) to take care immediately of any departure of the distributor brushes from the desired phase position, while the natural period of the controlling tuning fork is changed to prevent, as 110 much as possible, the necessity of future clock hand corrections.

115 Furthermore I do not limit the application of my invention to synchronous systems employing rotary current distributors using the Bandst code, nor to the suspension of signals for one revolution of the distributor, nor to the transmission of grounding impulses and current reversals in the particular order disclosed. The invention is applicable to synchronous systems of various types, including those in which contacts are periodically closed by rotating cams or vibrating reeds. The length of the period during which signal transmission is suspended for stabilizing purposes is determined by the characteristics of the cable to which it is applied, and may be less or greater than the time of a complete 125 cycle of operation of the synchronous apparatus. Likewise the character of the 130

stabilizing impulses required on different cables may differ; under some conditions it may be desirable to transmit only current reversals and under other conditions the best treatment may be to ground, or open, the cable for the entire period preceding the synchronizing impulse. Under some conditions one synchronizing impulse may be sufficient for synchronizing purposes and under others a series of several impulses may be required.

In view of the above facts it is clear that the invention is not limited to the particular disclosure in the drawings but only as defined in the following claims.

15. Claims.

1. The method of signalling over a high capacity cable which comprises transmitting signal impulses, interrupting the signal transmission at intervals and before resuming signal transmission, restoring the cable to a predetermined electrical condition and thereafter transmitting a synchronizing impulse.

2. The method of signalling over a high capacity cable which comprises signalling for an interval, thereafter clearing the cable of unbalanced residual charges and thereafter transmitting a synchronizing impulse.

3. The method of signalling over a high capacity cable which comprises signalling for periodic intervals and during intervening periods transmitting a series of clearing out pulses of alternately opposite polarity.

4. The method of signalling over a high capacity cable which comprises transmitting and receiving signal impulses for an interval of time, thereafter transmitting for a shorter interval of time a series of equal clearing out impulses of alternately opposite polarity, and thereafter transmitting and receiving a synchronizing impulse.

5. The method of signalling over a high capacity cable which comprises transmitting a series of signal impulses, thereafter grounding the cable at the transmitting station, and thereafter transmitting a synchronizing impulse.

6. The method of signalling over a high capacity cable which comprises transmitting signal impulses for a predetermined period, thereafter grounding the cable for a predetermined interval, thereafter transmitting equal impulses of alternately opposite polarity for a predetermined interval, and thereafter transmitting synchronizing impulses.

7. The method of signalling over a high capacity cable which comprises transmitting signalling impulses for a predetermined interval of time, thereafter transmitting equal impulses of alternately opposite polarity for a predetermined interval, thereafter grounding the cable for a predetermined interval, and thereafter transmitting a synchronizing impulse.

8. In a synchronous telegraph system comprising a high capacity cable, transmitting means for transmitting thereto, in succession, a series of signal impulses, a series of equal clearing out impulses of alternately 70 opposite polarity and a synchronizing impulse.

9. In a synchronous telegraph system comprising a high capacity cable, transmitting means for transmitting thereto in succession, 75 a series of signal impulses, a grounding impulse, a series of equal impulses of alternately opposite polarity, and synchronizing impulse.

10. In a synchronous telegraph system 80 comprising a high capacity cable, transmitting means for transmitting thereto in succession a series of signal impulses, a grounding impulse, a series of signal impulses of alternately opposite polarity, and a synchronizing impulse; and receiving means operating synchronously with said transmitting means comprising means for receiving and recording (or repeating) signals, synchronizing means responsive to said synchronizing impulse for synchronizing said receiving means, and timing means for rendering said signal receiving means responsive to impulses received over the cable only when signal impulses are being transmitted 95 and for rendering said synchronizing means responsive to impulses received over the cable only when synchronizing impulses are being received.

11. In a synchronizing telegraph system 100 comprising a high capacity cable, means at one end of said cable for transmitting signal impulses thereto, means for grounding said conductor of said cable, means for transmitting equal impulses of alternately opposite 105 polarity, and timing means for causing said first means to transmit signals to said conductor for a predetermined interval, for causing said second means to ground said conductor for a predetermined period thereafter, and 110 for causing said third means to transmit to said conductor equal impulses of alternately opposite polarity for a predetermined interval thereafter, and means at the opposite end of said cable operating synchronously 115 with the transmitting means for receiving said signal impulses and said synchronizing impulse.

ALLISON ANDREW CLOKEY.
